Patented Oct. 10, 1916.

UNITED STATES PATENT OFFICE.

ALBEN E. LUNDELL, OF NEW YORK, N. Y., ASSIGNEE TO WESTERN ELECTRIC COMPANY, INCORPORATED, OF NEW YORK, N. Y., A CORPORATION OF NEW YORK.

SELECTOR-CONTROLLER.

1,200,860.

Specification of Letters Patent. Patented Oct. 10, 1916.

Application filed January 3, 1915. Serial No. 39,843.

To all whom it may concern:

Be it known that I, ALBEN E. LUNDELL, a citizen of the United States, residing at New York, in the county of Bronx and State of New York, have invented certain new and useful Improvements in Selector-Controllers, of which the following is a full, clear, concise, and exact description.

This invention relates to controllers for governing the operation of selectors, such as the automatic switches and like apparatus of telephone exchanges and its objects are standardization and economical use of registering equipment associated therewith. It is applicable especially to operators' controllers in semi-automatic systems.

Each operator's position in a semi-automatic system is provided with one or more controllers, each comprising a sender adapted, in repeated operations and acting under control in succession of a plurality of adjustable registers, to set up through a series of automatic switches, any desired telephone connection. The registers are first adjusted by the operator in accordance with the number or other designation of the wanted party's line or station, whereupon the sender performs its function automatically. The senders have no normal position, *i. e.*, they remain in their last adjusted position. The sender is usually associated with a connecting circuit selector or "cord finder" which connects the sender with a cord circuit when the latter is taken for use.

In large telephone exchanges, constructed in accordance with plans heretofore known, the number of selectively operable switches may vary in accordance with the connection desired.

According to the present invention, means such as a class register controller of the sequence switch type is provided for determining the number of registers to be effectively associated with the sender. Supposing that four registers are provided for controlling successively four selective setting operations. If all the four registers are adjusted and only three selective setting operations are necessary for establishing a connection, then in accordance with this invention the controlling circuit is maintained open for a sufficient length of time to prevent the improper setting of the last selectively operable switch.

The sender is usually associated with a connecting circuit selector or "cord finder" which connects the sender with a cord circuit when the latter is taken for use. Two sequence switches are employed ordinarily in adapting the sender with the sender and to the cord circuit, respectively. The result is that all the sequence switches throughout the exchange system do not vary in construction and their adjustment has the same number of analog switchings positions, differing only in the number and shape of curvings of their cams in contact disks.

In large telephone exchanges, constructed in accordance with plans heretofore known, the sender would require an unusually large sequence switch or a plurality of them to take care of the large number of selecting operations required. The present invention, however, diverts this difficulty by causing one sender sequence switch to operate in repeated cycles to contact the registers one after another with the sender. As far as the last mentioned phase of the invention is concerned the present application is a continuation of my copending application Serial No. 353, filed January 3, 1915.

The invention will be described more in detail by reference to the accompanying drawing, in the upper part of which is shown in skeleton outline a switching circuit between telephone stations 1 and 2, and 1 and 2'. In the middle part is a cord finder 3 and a sequence switch 4 associated therewith, and in the lower part is a sender 5. Sequence switch 6 associated therewith, a class register controller 7 of the sequence switch type, and a class register 8. Contact contacts 8, 9, and 10 are connected to switches 4, 6 and 5, respectively. They determine the resting positions as follows: The cord finder sequence switch 4, *normal*; 2, *awaiting register*; 8, "thousands" and "hundreds" selecting; 10, "tens" and "units" selecting, and the sender sequence switch 5, *normal*; 1, first cycle, "thousands"; 1, first cycle, "hundreds"; 2, second cycle, "tens"; 4, second cycle, "units" selecting. The class register controller has no normal position.

When the subscriber at station 1 calls, the operator inserts the plug 11 in the jack 12, extending the calling line to the cord circuit

12. The sender 5 is thereupon connected by the cord finder 3 into operative relation to a first selector 13, then if connection is desired to station 2, to a second selector 14 and finally to a final selector 15. The selecting operations take place in accordance with the called party's number recorded on the set of registers 7, which as shown, may include a "thousands" 21, a "hundreds" 25, a "tens" 23, and a "units" register 27. These registers may be adjusted in any desired manner by turning each of the contact arms 29 to any of ten contact points (0) to (9). As shown in the drawing the registers are adjusted to record the number 2101.

The sender may be as shown, of the well known counting relay type. It comprises a double series of counting relays operable in sequence by action of a stepping relay 16. The latter is intermittently energized and deenergized by the intermittent action of a reverting impulse commutator switch on a power driven selector, the details of which, being well known are not shown. The first counting relay in the series to be energized in each selecting operation, is determined by the point recorded on the register, which at the moment is in circuit with the contact 17 of the stepping relay 16. When the proper number of steps of the selector are taken, the zero counting relays 18 and 19 operate; the former opening the controlling circuit to the selector and stopping it, and the latter closing a circuit for moving the sequence switch 6 into its next resting position. This sequence switch 6 is not required to have as many resting positions other than normal (1) as there are registers in the set 7, but only as many as a fraction, say one half, of them. Only four registers are shown as this is a sufficient number to fully illustrate the application of the invention to a system of any size.

In applying the invention to the system of four registers shown, the sequence switch 6, would require but two off-normal resting positions, say positions 2 and 4. In position 2 the arm 29 of the "thousands" register 21 is connected at contact 22 and the arm 29 of the "tens" register 25, at contact 24. In position 4, the arm 29 of the "hundreds" register 25 is connected at contact 26 and the arm 29 of the "units" register 27 at contact 28. These are but partial connections of the registers to the stepping relay contact 17. They are completed, however, through successive contacts 31 and 32 of the sequence switch 4, occurring in its off normal resting positions 8 and 15, respectively. The operation is as follows: Assuming the sender 5 to have been connected by the cord finder 3 to the cord circuit 12 and the registers to be adjusted as shown for calling party, No. 2101, contact 33 is then closed to start the selecting operations. This com-

pletes a circuit—ground, 33, 72, 4, battery—70 which sends the cord finder sequence switch 4 out of normal 1, into position 2. The operator depresses also a key 73 and if switch 70 is in position 6 a circuit is closed—ground, 73, 74, 70, battery—for moving this switch into position 1. A circuit is now closed—ground, 73, 75, 76, 77, 4, battery—and sequence switch 4 is driven into position 8. While passing positions 4 to 6, 75 there is closed a circuit—ground 34, 35, 6 battery—which sends the sender sequence switch 6 out of normal 1, into position 2, wherein the connection between the sender and selector apparatus is made effective by 80 the closing of a contact 36, and whereupon the first (say "thousands") selecting operation takes place. The stepping relay 16 is now intermittently energized in accordance with the well-known reverse impulse system 85 of selector control.

The first closure of the stepping relay contact 17 results in the action of counting relay 37, the first opening in the action of relay 38, the second closing in the action of relay 39, the second opening in the action of relay 41, the third closing in the action of relay 42, and the third and last opening in the action of relays 18 and 19. The circuit for relay 37 is as follows: ground, 17, 31, 95 22, 43, 44, 37, battery; for relay 39; ground, 17, 31, 22, 43, 45, 46, 39, battery, and for relay 42; ground, 17, 31, 22, 43, 45, 47, 42,

The successive openings of contact 17 result in the unshunting and action as stated of relays 38, 41, 18 and 19. Relay 18 by 100 opening the selector control circuit at contact 49, terminates the "thousands" selecting operation. The counting relays are for 105 the moment locked in circuits through contacts 51, 52 and 53 of relays 37, 39 and 42, respectively, and sequence switch contact 54. But the sequence switch 6 is immediately caused to advance from position 2 to 4 by 110 the closing at contact 55 of relay 19 of a circuit—ground, 37, 55, 6, battery; and in passing positions 3 the locking circuits of the counting relays are opened at contact 54. The sender is thus restored for the next 115 or "hundreds" selecting operation which now takes place. The "hundreds" register 25 having been adjusted to point (1) and contact 26 being closed instead of 22, the first closure of the stepping relay contact 120 17 results in the action of counting relay 39 instead of 37 as before, the circuit being as follows: ground, 17, 31, 26, 56, 46, 39, battery. In this selecting operation therefore two closures and two openings of contact 17 take place, thereupon relays 18 and 19 act as before, the former terminating the "hundreds" selector movement and the latter causing the sequence switch 6 to be moved out of position 4. The next, and a 125 130

number of succeeding selecting operations, might take place in, say, positions 6, 8, etc., of sequence switch 4, but in the simplified system shown, it is assumed that the "hundreds" is the last of the first series of selecting operations. Upon leaving position 4, therefore, the sequence switch 6 completes its first cycle and returns to normal (1) again. In passing positions 15 to 1, there is closed a circuit—ground 57, 58, 4, battery—which sends the sequence switch 4 out of position 8 and into 15, and sequence switch 6 is sent on to position 2 again by a second closing of circuit—ground, 34, 35, 6, battery.

15 The first (or "tens") of the second series of selecting operations now takes place. As the "tens" register is adjusted to the (0) point and contacts 32 and 24 are closed, the first closure of the stepping relay contact 17 in this selecting operation energizes the zero counting relay 42, the circuit being as follows: ground, 17, 32, 24, 59, 42, battery, and the first opening causes relays 18 and 19 to act as before. Sequence switch 6 is sent on to position 4 again and the last or "units" selecting operation takes place. In this operation, the first closure of the stepping relay contact 17, energizes counting relay 39, the circuit being as follows: ground, 17, 32, 29, 30 61, 46, 39, battery, and two closures and two openings occur. This completes the several selecting operations necessary for the assumed call No. 2101, in the simplified system of the drawings. It will be understood however, that more than three (usually ten) pairs of counting relays may be employed so as to provide for points 3 to 9, as well as 0 to 2 of the registers. As previously stated also, a greater number than four selecting operations may be provided for. Obviously the selecting operations, in accordance with the organization of sequence switches disclosed, may if desired be divided into more than two series, and caused to take place 45 in successive cycles of the sender sequence switch 6, occurring respectively in successive positions of a single cycle of the word finder sequence switch 4. If connection is desired to station 2', selector 13 will have to be set onto a trunk leading to connector 15', and then this connector will be set by means of two series of selective impulses.

Supposing that the number of station 2' is 101, the operator adjusts registers 21, 23 55 and 27 accordingly, and depresses a key 80 instead of key 73 because the key 80 controls the movement of selector 13 onto contacts in which trunks leading to connector 15' terminate. A circuit is closed—80, 81, 60 70, battery—for driving the register controller 70 out of its last resting position (1) into position 6. Sequence switch 4 is driven out of position 2 into 8 by a circuit closed from ground through 80, 82, 76, 77, 4, to 65 battery.

Selector switch 13 is set in substantially the same manner as above described. After the sending out of the "thousands" impulses and the moving or sequence switch 6 out of position 2 into position 4, relays 39, 41, 70, 42, 19 and 18 (register 21 being set on contact 1) become deenergized; relays 42, 19 and 18, however, become again energized in position 3 of this sequence switch, ground being supplied instead of contact 54, 75, through 83, 84, 85, 86, 18, 19, 42 to battery. Relay 18 maintains the controlling circuit open at contact 49, and as soon as sequence switch 6 reaches position 4 it will be driven into position 1 by a circuit—ground, 87, 55, 80, 6, battery.

Connector 15' is now set in accordance with the adjustment of registers 23 and 27 in the same manner as above described in connection with connector switch 15.

It will be thus seen that although register 25 was in an actuated position (1), selector 15' was not set under the control thereof, the effective association of this register with the sender being prevented by the operation 90 of the class register controller 70.

What is claimed is:

1. In a selector controller, a plurality of registers, a sender, means for successively associating said registers with said sender, 95 and means including a sequence switch for preventing the effective association of one of said registers with the sender.

2. In a selector controller, a plurality of registers and a sender for controlling a 100 plurality of selective operations, and means independent of said sender and registers for determining the number of selective operations to be effected.

3. In a selector controller, a sender, a 105 plurality of actuated registers, means for successively associating said registers with the sender, and independent means for preventing the effective association of all the registers with the sender.

4. In a selector controller, a plurality of registers, a sender, means including a sequence switch operating in successive cycles, to successively associate said registers with said sender, and independent means for preventing the effective association of one of said registers with the sender.

5. In a selector controller, a plurality of series of registers, a sender, means including a sequence switch operating in successive 120 cycles, to successively associate the registers in one series after another with said sender, and independent means for preventing the effective association of a register of one series with the sender.

6. In a selector controller, a plurality of series of registers, a sender, a sequence switch operating in several cycles and in each cycle associating the registers of each series successively with said sender, and in 125

dependent means for preventing the effective association of the last register of the first series with the sender.

7. In a selector controller, a plurality of registers, a sender, means including a sequence switch operating in successive cycles, to successively connect said registers to said sender, and means controlled by said sender for operating said sequence switch.
- 10 8. In a selector controller, a plurality of series of registers, a sender, and means including a sequence switch operating in successive cycles, to successively connect the registers in one series after another to said sender.
- 15 9. In a selector controller, a plurality of series of registers, a sender, a sequence switch operating in several cycles and in each cycle switching the registers of each
- 20 series successively into partial connections to said sender, and means acting during successive cycles of said sequence switch to complete the partial connections in one series of registers after another.
- 25 10. In a selector controller, a plurality of registers, a sender, two sequence switches, one moving in successive cycles while the

other moves in a single cycle to successively connect said registers to said sender, and means controlled by said sender for operating said sequence switch moving in successive cycles.

11. In a selector controller, a plurality of series of registers, a sender, means including a sequence switch operating in successive cycles, to successively connect the registers in one series after another to said sender, and means controlled by said sender for operating said sequence switch.

12. In a selector controller a plurality of series of registers, a sender, a sequence switch operating in several cycles and in each cycle switching the registers of each series successively into partial connections to said sender, means acting during successive cycles of said sequence switch to complete the partial connections in one series of registers after another, and means controlled by said sender for operating said sequence switch.

In witness whereof, I hereunto subscribe my name this 31st day of December A. D., 1915.

ALBEN E. LUNDELL.
